TIME INTERVAL INDICATING AND RECORD-
ING APPARATUS

Alma A. Pitt, Chicago, Ill.

Application April 25, 1931. Serial No. 532,846

7 Claims. (Cl. 235—92)

This invention relates to automatic time interval registering apparatus; and more particularly to passenger elevator signal apparatus designed to register the interval of time a passenger, on 5 any floor of the building, has waited to receive elevator service.

The main objects of this invention are to provide means for currently informing the elevator starter or operator, or both, of the elapsed time 10 a passenger on any floor of the building, has waited for an elevator to answer his call; to provide apparatus to automatically record the class of service rendered, as indicated by the length of time passengers have been required to wait; 15 to provide automatic counters which will indicate the number of intervals of one or more predetermined lengths, that passengers throughout the building have waited for service; and to provide an automatic graphic record indicating the 20 number of intervals of each predetermined length, of waiting and the time of day that they occurred.

A specific embodiment of this invention is shown in the accompanying drawings, in which—

Figure 1 is a diagrammatic sketch showing an 25 end view of the apparatus and the circuits required for one floor.

Fig. 2 shows a magnetically operated counter linked to one of several recording pens marking 30 a continuous record on a traveling tape.

Fig. 3 is a diagrammatic representation of the apparatus required for two floors of a bank of elevators, showing the complete operating circuits and a side view of the contacting device.

The device shown in the drawings, comprises 35 a base 1 on which is mounted a coil bracket 2 supporting an actuating coil 3 having feed wires 4 and 5 connected to a hall signal switch relay which may be of any usual type whereby the 40 circuit is intermittently closed and opened. Pivoted at 6 on the coil bracket 2 is an armature 7 which carries a sliding contactor member 8, on one side of which is cut a rack 9. The rack 9 cooperates with a drum 10 having gear teeth on 45 its periphery, which when in mesh elevates the sliding contactor member at a constant, fixed speed.

At the upper end of the sliding member 8 is an 50 insulating block 11, on one side of which is mounted a lighting-circuit-contact shoe 12 to which is attached a flexible conductor 13. The conductor 13 connects the shoe 12 with the positive side 14 of the electric light circuit in which is a lamp 15. On the opposite side of the block 55 11 is a counter and recorder circuit contact shoe

16 attached to a flexible conductor 17 connected with a negative lead wire 18.1.

Bus or terminal bars 19, 20 and 21 are located in branches of the negative side of the lighting circuit 18 and are arranged to form contacts for 60 the shoe 12.

In circuit with the bus or terminal bar 20 is a 65 flasher 22, comprising a rotary current interrupter having long contacts 23 and short contacts 24. In circuit with the bus or terminal bar 21 is another flasher 25 comprising a rotary current interrupter having uniform contacts 26.

The counting and recording circuit bus or terminal bars 27, 28 and 29 are each connected to 70 operating coils 30, 31 and 32 respectively, located in branches of the positive side 14.1 of the counter and recorder operating circuit.

Figure 2 shows only one of the three counter and recorder operating coils, shown in Figure 1, and only one counter and complete recording 75 pen and linkage, and for this description we will refer to coil 30 only, the others being the same. The core 33 of the coil 30 is linked to a counter 34 and to a recording pen 35. The pen 35 is arranged to coat with a continuously traveling 80 tape 36 to produce a graphic record of every action of the core 33 in the coil 30 as transmitted by the linkage 37.

In operation, the drum 10 and the flashers 22 and 25 are continuously driven at a constant, 85 fixed speed by a motor.

The lighting circuit is operated from lead wires 14 and 18, and the counting and recording circuit from lead wires 14.1 and 18.1. The actuating coil 3, through wires 4 and 5, is energized 90 through the closing of its circuit by means of any intermittently operated device, such as the usual relay 38, provided for each floor and actuated by the pushing of an up-or-down button of a respective elevator signal switch 39.

When so applied to elevators, the time indicated and registered, for example, will be the 95 interval between pushing the button of the hall signal switch 39, which closes the signal relay 38 and energizes the respective coil 3, and the arrival of the elevator car at the floor on which that signal switch 39 is located, at which point the contact shoe 40 on the elevator bridges the contacts 41 and 42 and closes a circuit which operates to open the relay 38 and automatically de- 100 energize the coil 3. When the circuit, through the actuating coil 3, is closed, the movement of the armature 7 toward the coil 3 will cause the rack 9 on the sliding member 8 to engage with the teeth on the constantly rotating drum 10, 110

which elevates the sliding member at a constant speed to contact successively the terminals 19, 20 and 21.

The distance the sliding member will travel depends upon the time that the actuating coil 3 has been energized; that is, the time required by the elevator to answer a waiting passenger's signal. When the sliding member 8 has reached its highest point, it will ride on the lowest notch of the rack 9 and will be held in that position until the armature 7 is released through the de-energizing of the actuating coil 3. When the armature 7 has been released by the coil 3, and the sliding member 8 has been thereby released from the drum 10, the member 8 will be immediately returned to its lowest or initial position by the action of the force of gravity.

When an armature 7 is drawn toward its actuating coil 3 after the same is energized by its respective hall signal relay, the respective lighting circuit is instantly closed by way of wires 14 and 13, the lighting contact shoe 12, the terminal bar 19 and the wire 18, thereby causing the respective light 15 to give a steady signal indicating that a passenger is waiting for service at the floor represented by that signal. When a definite, predetermined time-interval has elapsed, the shoe 12, being constantly moved upward by the coaction of the sliding member 8 and the drum 10, is pushed past the terminal bar 19 and comes into contact with the terminal bar 20.

In circuit with the terminal bar 20 is a flasher 22 with alternating long and short contacts giving dot-and-dash flashes on the signal light 15, indicating that a certain predetermined interval has elapsed since the waiting passenger first called for service. When the contact shoe 12, in its upward travel leaves the terminal bar 20, it comes into contact with the terminal bar 21. In circuit with the terminal bar 21 is a flasher 25 arranged with contacts of equal width to give a uniform dot signal, thereby indicating the lapse of a second predetermined time-interval since the waiting passenger's first call for service.

When the contactor actuating circuit is opened, and the armature 7 is released by the coil 3, the sliding member 8 falls away from the driving and elevating drum 10 and the contact shoe 16 strikes the counter and recorder circuit terminal bars directly opposite the lighting circuit terminal bars with which the shoe 12 has contacted. For example, if the shoe 12 is in contact with the terminal bar 20 at the instant the actuating coil 3 is deenergized through the opening of the actuating circuit relay connected to the leads 4 and 5, as caused by an elevator car stopping at the floor from which the signal originated and automatically closing the circuit through the contacts 41 and 42, and the sliding member 8 falls away from the driving drum 10, the contact shoe 16 will strike on the terminal bar 28, thereby actuating the counter and recorder operated by the coil 31 and thereby recording the lapse of the predetermined time-interval as represented by the terminal bars 20 and 28.

In an ordinary installation of this device, a signal light 15, a sliding member 8 with two contacts 12 and 16 mounted thereon, and an actuating coil 3 coacting with an armature 7 would be furnished for each floor of the building. One driving drum 10, one of each type of flasher, one set of terminal bars each, for the lighting and

registering circuits and registers for each time-interval to be indicated would be furnished for each bank of elevators.

The assembly of this equipment, with the exception of the signal lights and the other registering devices, is arranged in a compact form, preferably as a unit as shown in Fig. 3, comprising a single drum 10 of sufficient length to accommodate the desired number of sliding members 8, a plurality of sliding members arranged parallel to each other and in a single row parallel to the axis of the drum, terminal bars and flashers. Each sliding member with its supporting armature 7 is arranged transversely of the drum axis and adjacent the drum periphery as shown in Fig. 1. An actuating coil 3 is provided for each sliding member and armature and is electrically connected to a respective hall signal switch relay 38 so as to be energized when the said relay is closed by operation of the hall signal switch or button 39. In the form shown the terminal bars are arranged parallel to each other, above and to one side of the drum 10, in spaced pairs extending parallel to the drum, and are disposed so that the sliding members 8 and the contact shoes 12 and 16 will travel between them and successively contact one bar of each pair accordingly as they are traveling upwardly or downwardly. One pair of terminal bars is provided for each time interval that is to be registered and each bar is of sufficient length so that it can be contacted by all of the sliding members. The flashers may be arranged adjacent the drum 10 and are preferably driven by the same driving means actuating the drum. The drum driving means shown is a constant speed electric motor 43 properly geared to the drum so as to rotate the same at a definite predetermined speed.

The signal lights, one representing each floor, would be installed in a convenient place and arrangement to inform the elevator starter of the time a passenger has been waiting for elevator service, and the counters and recorders, one of each for each predetermined time-interval, would be installed in a location convenient to the manager of the building.

The unit comprising the driving drum, with flashers and contactor equipment would all be located at one place, either in the basement of the building or in the elevator equipment pent-house.

When the hall signal switch or button 39 on a certain floor is operated by a waiting passenger the respective coil 3 is energized and its armature 7 is actuated causing the contactor shoes to be moved, at a constant speed, transversely of the terminal bars. Each time a terminal bar is contacted an individual circuit is completed and a means is actuated to register the particular time interval represented by such terminal bar.

With this arrangement the elevator starter may be constantly advised by means of lights as to the floors on which passengers are waiting for service, as well as the time-intervals that the passengers have been required to wait. Also the manager of the building may be constantly advised by means of counters and recorders as to the class of service the elevator system is giving as indicated by the total number of the different predetermined time intervals that have elapsed while passengers on all floors of the building have waited for service. The graphic recorder is arranged to show the time of day that each lapse of any of several predetermined time intervals has occurred.

5 The terms "register" and "registering", as used in the foregoing description and the appended claims, are intended to signify and include within the spirit of their meaning, the means severally or collectively to indicate, record and count; and the acts of indicating, recording and counting.

10 Although but one specific embodiment of this invention has been herein shown and described, it will be understood that certain details of the construction shown may be altered or omitted without departing from the spirit of this invention as defined by the following claims:

I claim:

15 1. In time interval registering apparatus, an actuating coil, a plurality of registers respectively registering different intervals of predetermined lengths, and means governed by the length of time said actuating coil is energized to operate the respective registers.

20 2. In time interval registering apparatus, an actuating coil, a plurality of registers respectively registering different intervals of predetermined lengths, and means governed by the length of time said actuating coil is energized to operate the respective registers when the actuating coil is deenergized.

25 3. In time interval registering apparatus, an actuating coil, means registering different intervals of predetermined lengths that said actuating coil is energized, and automatic means controlled by said actuating coil and operating at a constant predetermined rate for operating said registering means.

30 35 4. In time interval registering apparatus, a register operating circuit, an actuating coil, a continuously operated driving mechanism, a series of terminals on said register circuit, a sliding contactor arranged to engage said terminals successively; said sliding contactor being moved to engage said terminals by said driving mechanism during the interval when said actuating coil is energized, and registers for registering time intervals of respectively different lengths that said actuating coil is energized.

40 45 5. In time interval registering apparatus, a

continuously operated driving mechanism, an actuating coil, a contactor driven by said driving mechanism, said contactor being moved into driving relation with said driving mechanism by said actuating coil, and means operated by said contactor for registering intervals of predetermined length of operation of said actuating coil. 80

6. In time interval registering apparatus, a register operating circuit, an actuating coil, a continuously operated driving mechanism operating at a constant fixed speed, a series of terminals on said register circuit, a sliding contactor arranged to engage said terminals, said sliding contactor being moved to engage said terminals by said driving mechanism during the interval when said actuating coil is energized, and registering means respectively associated with said terminals and operated by said contactor for registering respectively different intervals of predetermined lengths that said actuating coil is 95 energized. 90

7. In a time interval registering apparatus, an actuating coil, an actuating circuit controlling said actuating coil, a register operating circuit having a series of branch circuits, a terminal and means to operate a register in each of said register operating branch circuits, a sliding member having a contactor mounted thereon and arranged to engage said terminals successively, said sliding member being controlled by said actuating coil, a constant speed driving mechanism arranged to engage with said sliding member when said actuating coil is energized and to cause said contactor to advance at a constant rate and to engage successively certain of said 105 register operating terminals, said terminals being spaced apart a distance proportionate to certain predetermined time intervals, and registers actuated through said register operating circuit to register respectively different intervals of pre- 110 determined duration that said actuating coil is energized, said sliding member being normally urged toward an initial position disengaged from said driving mechanism and from said terminals when said actuating coil is de-energized. 115 120
